US00D730329S

(12) **United States Design Patent**
Man

(10) **Patent No.:** **US D730,329 S**
(45) **Date of Patent:** **** May 26, 2015**

(54) **RFID TAG INLAY**

(71) Applicant: **Megabyte Limited**, Hong Kong (HK)
(72) Inventor: **Chun Sing Matthew Man**, Hong Kong (HK)
(73) Assignee: **MEGABYTE LIMITED**, Hong Kong (HK)
(**) Term: **14 Years**

(21) Appl. No.: **29/489,229**

(22) Filed: **Apr. 28, 2014**

(51) **LOC (10) Cl.** 14-03
(52) **U.S. Cl.**
USPC **D14/230**

(58) **Field of Classification Search**

USPC ..... D14/138, 230-238, 299, 358; D12/42, D12/43; 343/700 MS, 700 R-705, 711-713, 343/735, 736, 741, 748, 767, 795, 819, 840, 343/846, 866, 871-908; 455/90.2, 90.3, 91, 455/128, 269, 344, 347, 562.1; 333/193, 333/195

Primary Examiner — John Windmuller

(57) **CLAIM**

The ornamental design for an RFID tag inlay, as shown and described.

DESCRIPTION

The sole FIGURE is a top plan view of an RFID tag inlay showing my new design.

The solid black areas constitute the entirety of the claimed design. All elements of the claimed design are flat and coplanar.

1 Claim, 1 Drawing Sheet
